GRIZZLY AND SCREEN FOR GRADING MATERIALS

William Ross, Surbiton, England

Application January 8, 1943, Serial No. 471,727
In Great Britain March 17, 1942

4 Claims. (Cl. 209—307)

This invention relates to screens for grading materials and particularly to what are commonly known as grizzlies and screens such as are described, for example, in my prior British patent specifications Nos. 123,201, 179,562 and 297,706, and which in general comprise two sets of transverse bars supported substantially horizontally and arranged to move in closed orbits of different lengths, which orbits, however, coincide in the screening zone in which the said bars will be separated by spaces of predetermined size. With the divergence of the orbits after passing the screening zone the spaces between the bars should be automatically increased in size and attain a maximum size when the bars are traversing the sections of their orbits directly beneath the screening zone whereby "fines" (that is, the small pieces of material) which pass between the bars in the screening zone are passed freely through the spaces between said bars when traversing the lower or return portions of their orbits.

With such screening arrangements as hitherto adopted it has been found in general that trouble is caused by the heavy apron of bars pressing laterally or sideways due to a number of factors connected with the load and namely (a) the way in which the load is fed to the screen; (b) the way the load disposes itself on the screen, and (c) the way the load leaves the screen. It must be understood that the grizzly is normally employed under conditions where wagon loads up to 25 tons and containing pieces up to 5' cube and weighing up to 4 tons are crash dumped on to the feed end of the screen or grizzly. It is therefore obvious that the initial pieces of material reaching the grizzly may hit the bars thereof in a manner that will produce sideways forces. Sideways forces are also produced by the load on the apron of bars being more to one side and/or the apron being pressed out of level locally or wholly and by the uneven lateral discharge of the material from the grizzly due for example to a large piece leaving earlier than its neighbour or to a bank of smaller material "sluffing" off at one side, a trouble which is accentuated in the case of small and sticky material which may arrive at the discharge end in a bank 3' or 4' thick. At one moment the end of this bed may be steep—sometimes vertical, sometimes even overhanging—and the next moment it is 45° backwards after a slough has occurred. Such material has no "angle of repose" or "flow angle."

It will be understood that such movements as the above set up unusual side wear on the chains,

by which the grizzly bars are carried, and the sprockets, over which the chains at each side of the grizzly bars pass, and, especially when the apron is forced to one side at one place and held or forced to the other side in another place, the chain links break and/or the bar ends are bent or broken.

The object of my invention is to provide an improved construction which will be free from the defects and disadvantages above noted, and which will moreover enable a sideways feeding of the material on to the grizzly bars to be a practical possibility.

The invention consists in a grizzly or screen 15 of the kind comprising sets of main and secondary or drop travelling screening bars arranged in pairs and extending transversely to their direction of travel wherein means is provided adapted to restrict sideways or lateral movement of the 20 bars under operating conditions due to the action of the material loaded or supported thereon.

The invention also consists in a grizzly or screen of the kind described in my earlier patent specifications above referred to, wherein the 25 screening bars bear, in the screening zone, upon a track with which the bars engage through the medium of recessed portions thereof such that sideways or lateral local movement of the apron constituted by the bars in the screening zone is 30 restricted.

Also in accordance with the invention the links of chains connecting the screening bars together and serving to carry the bars through the screening zone are formed to have a certain amount of 35 clearance where they are connected with each other such that a limited amount of lateral bending or distortion of the chain at such points is permitted to take care of sideways or lateral thrusts imposed upon the screening bars by the 40 material received thereon.

The invention also consists in screening apparatus of the character described having further features hereinafter referred to.

In the accompanying drawings—
Figure 1 is a side elevational view of a grizzly or screen in accordance with the invention,

Figure 2 is a half plan view of Figure 1,

Figure 3 is an end view of Figure 1,

Figure 4 is an enlarged part sectional and fragmentary plan view of the grizzly or screen bars,

Figure 5 is a section on the line A—A of Figure 4,

Figure 6 is a section on the line C—C of Figure 4.

In carrying my invention into effect in one convenient manner a grizzly or screen is provided which, like the constructions according to my earlier specifications, comprises alternate main bars 1 and secondary or drop bars 2 extending transversely between a pair of side and endless chains 3 to which the main bars 1 are pivotally connected at their ends and in order to afford a certain amount of lateral flexibility I provide the chain links 4, connected to the main bars, with their outer ends 5 somewhat narrower than their inner ends, effected for example by tapering their outer ends inwards (as shown in Figure 4), whereby a clearance D exists between the outer ends of the main links 4 and the side links 6 connected between the main links which is sufficient to permit a lateral local bending of the chains up to a certain extent without straining or breaking, there being enough clearance 7 between the hubs 6a of the side links and the spigoted pivot ends 1a of the main bars to permit such lateral movement to take place and a further clearance 8 being provided for between the holes in the main links 4 and the bearing surfaces therefor afforded by the exterior surfaces of the corresponding hubs 6a to assist in this direction. The drop bars 2 have spigoted pivot ends 2a engageable within bushes 2b on lever arms 2c, in turn pivoted through bushes 2d at their opposite ends about the inner ends of the corresponding hubs 6a mounted upon the spigoted ends of the main bars and, as shown in Figures 4 and 5, a certain amount of clearance E is also provided between the various bearing surfaces thus provided.

Disposed to extend longitudinally along the inside of each chain and situated, as shown in Figures 1-3, near the upper run of the assembly of main and drop bars there is a plate or track 9 upon the upper edge of which the corresponding end portions of the grizzly bars bear while they move through the screening zone but whereas the drop bars 2 rest freely upon the track plate or are only slightly recessed, as indicated at 10 in Figure 4, to engage therewith the main bars 1 are deliberately recessed, as indicated at 11, at the portions thereof which come opposite the upper edges of the track plates so that sideways or lateral movement of the apron, constituted by the assembly of main and drop bars, is restricted due to the engagement of the track plates within the recesses of the main grizzly bars. However, such recessing of the main grizzly bars is preferably not such as will preclude some lateral movement of the apron. Thus when the recesses in the main bars are in the form of annular recesses of channel form there is preferably some clearance provided between the sides 12 of the recesses and the side walls 13 of the portions of the tracks which engage therein. Preferably, however, the recesses in the main grizzly bars are of flattened V-shape in cross section and extend beyond each side of the track plates, the latter being shaped upon their upper edges to conform with the central portions of the recesses in the grizzly bars. In order to further facilitate the supporting of the drop bars when the latter pass through the screening zone cooperative abutment means are mounted on side links 6 and on the lever arms 2c preferably being in the form of nut and bolt arrangements 51 be engaged in the links in such manner that the heads are prevented from rotating, the heads constituting the abutments proper on the links, and they cooper-

ate in turn with lateral lugs 511 on the lever arms 2c, the arrangement being shown in Figure 4.

The track plates may, as shown in Figure 3, be supported in position through the medium of springs 14 which permit a limited amount of vertical movement of the plates to take place to afford a kind of cushioning effect when the material is loaded upon the screening bars.

To provide for an even loading of the grizzly 10 with the material to be screened, I may provide, in one of its simplest forms, a barrier 16 above the grizzly which serves to impose a limit to the maximum depth of the bed of material at any point across the width of the grizzly and causes 15 attempted excesses of material at one point of the width of the grizzly to go to other unoccupied parts of the width thereof. Such barrier (which may consist of a plate supported above the grizzly to extend transversely across the grizzly bars near the feed end of the grizzly and, of course, be vertically spaced from the grizzly bars) may be adjusted to be higher at one side than the other to correct permanent faults in or tendencies of feed.

25 I claim:

1. A grizzly or screen of the kind comprising endless chains, sets of main and secondary transverse bars arranged in pairs with the main bars of each set supported at their outer ends upon the endless chains to lie substantially horizontally and arranged to move in closed orbits of different lengths, which orbits, however, coincide in the upper run which constitutes the screening zone, a track arranged beneath the upper run 30 of the assembled bars and all of the bars being recessed near their ends to engage with the track to restrict sideways or lateral movement of the bars.

2. A grizzly or screen according to claim 1 40 wherein the bars rest freely on the track in the screening zone through the medium of the recessed portions of the bars, which recessed portions are of flattened V-shape in cross section, and in the case of the main bars have their bevelled side walls extended beyond each side of the corresponding track whereby sideways or lateral movement of the main bars in the screening zone is definitely restricted.

3. A grizzly or screen of the character described comprising spaced horizontal shafts, spaced sprockets thereon, endless chains operating about the sprockets, sets of main and secondary transverse bars arranged in pairs with the main bars of each pair operatively connected 50 with the chains while the secondary bars are operably connected to the main bars so as to have a swinging movement, tracks arranged longitudinally beneath the upper lays of the chains for maintaining the bars in a horizontally supported position, the main and secondary bars being grooved near their ends to engage the tracks to restrict side-wise or lateral movement of the bars as the bars pass through the upper lay which constitutes the screening zone, and means for 55 yieldingly supporting the tracks.

4. A grizzly or screen of the character described comprising spaced horizontal shafts, spaced sprockets thereon, endless chains operating about the sprockets, and including main and side links to which the main links are connected, main and secondary transverse bars arranged in pairs and having their respective ends trunnioned with the trunnions on the main bars elongated and journaled in the side links, lever arms operatively connected to the side links and about the

elongated trunnioned ends and having the trunnioned ends of the secondary bars journaled therein so as to be swingably suspended relative to the main bars, tracks arranged longitudinally beneath the upper lays of the chains which constitute the screening zone for maintaining all of the bars in a horizontally supported position, the

main and secondary bars being also recessed near their ends to engage the tracks to restrict side-wise or lateral movement of the bars as the bars pass through the upper lay, and means for yieldingly supporting the tracks.

WILLIAM ROSS.
